UNITED STATES PATENT OFFICE.

GEORGE LANZENDOERFER, OF BOSTON, MASSACHUSETTS.

DIGESTER-LINING.

SPECIFICATION forming part of Letters Patent No. 744,769, dated November 24, 1903.

Application filed December 6, 1902. Serial No. 134,077. (No model.)

To all whom it may concern:

Be it known that I, GEORGE LANZENDOERFER, a citizen of the United States, residing at Boston, in the county of Suffolk and State 5 of Massachusetts, have invented a new and useful Improvement in Digesters and Lining-Bricks Therefor, of which the following is a full, clear, and exact description, reference being had to the accompanying drawings, 10 forming a part of this specification, in explaining its nature.

The invention consists in a digester which has a metal shell of the usual type and which is lined upon its interior with acid-resisting 15 bricks of a curved shape having a plain outer face and a deeply-corrugated inner face, the corrugations forming receptacles or pockets for a cement used in uniting the bricks to the shell and to each other. This provides a 20 structure in which the bricks may be set directly against the shell or bricks carried thereby and in which the joints between the bricks and the shell and the individual courses of brick are formed by a series of 25 rings or sections of cement arranged between the bricks and so as to, in effect, produce as many different joints and variety of joints as there are rings, the purpose of the invention being to provide a structure which shall offer 30 the greatest resistance to the strains to which a digester-lining is subjected and shall also offer under such conditions the least liability of the escape of the liquid of the digester from the lining to its shell or casing.

35 I will now describe the invention further, in conjunction with the drawings forming a part of this specification, where—

Figure 1 is a view of a portion of a digester looking from the interior thereof. Fig. 2 is a 40 detail view in section, enlarged; and Fig. 3 is a view in perspective of one of the bricks.

Referring to the drawings, A represents the usual type of digester shell or casing. It may or may not be lined upon its inner surface 45 with lead or other acid-resisting substance. To the inner surfacing of the shell or to the said lining, if one be used, there is then applied the bricks B in as many courses as may be desired. The bricks are alike, and each 50 is curved to conform to the curvature of the shell and has a smooth curved surface a and a corrugated back b, the corrugations extend-

ing crosswise the back and being relatively wide and deep and separated by relatively narrow intervening parts b' of the brick back, 55 which are substantially of the same size and the outer edges of which are arranged upon the same curve. These bricks preferably have flat sides and ends, the ends being somewhat inclined, as represented. The 60 bricks thus shaped will form, assembled together, a wall of the curvature of the digester-wall.

As many courses of brick may be used as desired, the first course being against the 65 wall of the digester-shell and the next course against the first course of brick, and so on. Each course is united to its support, whether digester-casing or brick, by means of cement applied to the corrugations to fill the same 70 and to bear against the support, the beds of cement thus held in the corrugations acting as so many bands to unite the courses of brick to their supports as well as to provide a series of independent joint-sealing packings 75 between the courses. The joints between the sides and edges of the bricks are sealed in any desired way. Because of the corrugations in the bricks which receive the cement a larger surface for the adhesion of the cement to the bricks is provided than where the surface is straight, while, on the other hand, sections of the back of each brick are brought into contact with its support, thus breaking the continuity of the cement and 80 causing a structure which consists of alternate bodies of cement and brick. The employment of the cement in this manner not only effects a structure of the character indicated, but it also furnishes a large number 85 of independent cement joints, which because of their independence provides an improved construction in that a crack or defect of any kind in one joint is confined to that joint and does not extend to other joints, so that 90 an imperfection in one part of the cement is confined to that and a very narrow one and does not necessarily extend to another, and the joints thus act to correct each other's possible defects, and thereby forms a multiplex 95 uniting and packing backing through which the liquid cannot be forced to the shell. The 100 bricks are also of some importance in that they can be assembled or built in the arch of

the digester without the use of temporary or false supports.

Having thus fully described my invention, I claim and desire to secure by Letters Patent of the United States—

1. The improvement in digesters herein described, the same consisting in the employment as a lining for the digester, of a number of courses of bricks having corrugated backs and independent joint-sealing packings contained in said corrugations uniting said bricks to each other and to the digester-shell.

2. A digester-lining consisting of a series of bricks each having a corrugated back of alternately, extended and recessed portions, cement filling said recessed portions of the

brick whereby the joints uniting said bricks to each other and to the shell of the digester are composed of lines of alternately, continuous extended sections of brick and lines of cement between the same within the recessed portions.

3. A digester, bricks having corrugated backs to bear against the shell and each other, and independent packings of cement contained in the corrugations and also serving to unite the bricks with each other and the shell.

GEORGE LANZENDOERFER.
